AIR RELIEF VALVE FOR STEAM RADIATORS

Gustav Richard Fickert, East Orange, N. J.;
 Minna Fickert administratrix of said Gustav
 R. Fickert, deceased

Application October 4, 1932, Serial No. 636,222

2 Claims. (Cl. 236—64)

This invention relates to means for controlling the inlet and outlet of air from steam radiators, the object being to provide an improved air inlet and outlet valve for steam radiators which 5 may be readily adjusted at any time and which when adjusted will automatically provide an opening and closing of the valve structure according to the temperature of the parts.

Another object of the invention is to provide 10 an air inlet and relief valve for steam radiators wherein a specially constructed expansible member is presented having a plurality of units formed so as to always return to their former position after each expansion.

15 Another object of the invention is to provide in a valve of the character described a resilient support for the expansible member so as to cause the valve and seat to engage with a yielding pressure.

20 In the accompanying drawing—

Figure 1 is a longitudinal vertical sectional view through a valve disclosing an embodiment of the invention, most of the interior part being shown in elevation;

25 Figure 2 is a perspective view of the resilient support shown in Figure 1;

Figure 3 is a vertical sectional view through the expansible member shown in Figure 1;

Referring to the drawing by numerals, 1 indicates a base which may be cast or otherwise formed. The base 1 is formed with an exteriorly threaded stem 2 adapted to be screwed into a suitable threaded aperture in a radiator to act as a connection between the valve and the radiator and also as a conductor for conducting air and steam from the radiator. The base 1 is provided with an internally threaded annular flange 3 adapted to have the threaded end of the casing 4 screwed therein. The casing 4 is provided with a restricted neck 5 at the upper part, said neck being internally threaded for receiving the threaded portion of an adjusting screw 6, which screw has a head 7 and a passageway 8 extending therethrough, said passageway having an enlarged bore 9 so that a valve seat 10 is formed.

The neck is provided with an enlarged portion 11 which is threaded exteriorly for receiving the cap structure 12 while the interior receives the head 7, which head is provided with a slot or groove 13 whereby a screw driver or other implement may be used for rotating the screw to secure the desired adjustment. Arranged internally of the casing 4 is an expansible member 14 which is supported on the bottom by a re-

silient adaptor or support 15 and which at the upper end carries a needle valve 16, which valve seats with the valve seat 10 for closing the passageway.

As shown in Figure 3, the needle valve 16 is 60 screwed into a nut 17 soldered or otherwise rigidly secured to the top unit 18 of the expansible member 14. From Figure 3 it will be noted that there are provided units 18, 19, 20, 21, 22 and 23, unit 23 being rigidly secured to 65 the plate 24 by solder or other means, this plate being formed with a tubular guide 25. Six units have been illustrated but it will be evident that a greater or less number can be used without departing from the spirit of the invention. 70

It will be noted that each unit is provided with a top header 26 and a bottom header 27, each header being dished or concaved inwardly while the flange 28 of header 26 is approximately twice as wide as the flange 29 of header 27. 75 This arrangement provides a good overlap for the flanges and presents a shoulder for the reception of solder along the corner or edge 30. This same structure is carried out through all the units, the top unit, however, being soldered 80 to the half eyelet rivet 31 and to the nut 17, while the bottom unit 23 is soldered to the half eyelet rivet 32 and to the flange 24.

It will be noted that each of the headers is provided with an offset portion 33 and that these offset portions come together or contact in all the intermediate headers so that the respective eyelet rivets 34 may be applied and thereby act to connect the respective headers. In addition to having eyelets arranged as shown 85 in Figure 3 the parts are also soldered so as to insure an absolutely air-and-liquid-tight connection. 90

By this arrangement there is free communication between the interior of the respective units, the communication being through the respective eyelet rivets 34. The concave or dish-shaped arrangement of the headers is important in that they permit the various units to expand until the headers are substantially straight or 100 flat, and when the temperature has decreased these headers will automatically and always return to their former position. A suitable expanding liquid 35 is placed in the units and, in fact, the units are completely filled with 105 this liquid so that when heat is applied the liquid will expand and will expand the various units.

In actual use it has been found that the use of six units all of a certain size will readily 110

- expand .04 inches and under most circumstances this is ample to secure the desired result. The liquid used may be quenching oil or other liquid which is non-drying and which will not vaporize 5 in ordinary heat and is free from oxygen. When the expansible member 14 is heated the liquid therein will expand and, consequently, the expansible member will elongate so as to move the needle valve 16 to a position against its seat 10.
- 10 Ordinarily when the adjusting screw 6 has been properly adjusted a free flow of air will be permitted when the clearance between the needle valve and the seat is from .015" to .02". However, as above mentioned, the device as 15 disclosed in the drawing will move at least .04".
- In order to relieve the expansion or elongation of the unit 14 when the same becomes appreciably expanded or elongated, the resilient support or adaptor 15 comes into play and yields 20 to a certain extent, thus preventing the expanding unit from pressing the needle valve against its seat with too much pressure, while at the same time permitting sufficient pressure to make for an appreciable tight connection in order to prevent loss of steam. The resilient support 15 may be of any suitable spring but it is 25 preferably made from some resilient material, for instance, such as brass, and a number of oppositely positioned saw cuts 36 and 37 are 30 provided whereby a spring or resilient structure is produced that will give a desired yielding action and at the same time provide the desired support. The resilient support is hollow, as shown in the drawing, so that the guide 25 35 may freely fit therein, and as the guide 25 is hollow it slides freely over the guiding center pin 38.
- When the device is first manufactured it is 40 adjusted at the factory so that the parts will appear substantially as shown in Figure 1 with the clearance between the needle valve 15 and the seat 10 about .02". It will be understood that the entire valve is cold, or rather at atmospheric temperature when this adjustment 45 takes place, and after the device has been shipped to the dealer and is eventually applied to a radiator it still remains adjusted in this manner, because the adjusting screw fits rather tightly and will not accidentally come out of 50 adjustment. If the parts are left in their original adjusted position they will function perfectly to permit air in the radiator to escape as the steam enters. When the steam enters the radiator at one end, the air by reason of the 55 pressure immediately begins to flow through the stem 2 into casing 4. This air is cold, or rather it is at atmospheric temperature, and, consequently, the expanding unit is not affected but the air escapes out past the needle valve. This 60 continues until the radiator is completely filled with steam and some of the steam or warm vapor passes through the stem 2 into the casing 4. As this is continued the expansible member 14 will become heated more and more, and 65 as the temperature is raised the expansible member will elongate and gradually move the needle valve 16 towards its seat. If the radiator becomes warmer and the expansible member becomes further expanded, the said expansion will 70 be taken up by the resilient support 15 so that

none of the parts will become injured or broken, notwithstanding the fact that the expansible member may become undesirably hot.

As the expansible member is absolutely air and liquid tight, the liquid 35 cannot escape and cannot evaporate, even if it is slightly capable of evaporation. The valve remains closed as long as the temperature of the expansible member 14 remains at a certain point, but as soon as the radiator begins to cool and the expansible member cools likewise, it will begin to contract because the units 18 to 23 are all resilient and all have a tendency to move back to the position shown in Figure 3.

By reason of this tendency whenever the liquid 35 contracts as it cools, the metallic parts of the expansible member will contract and gradually move the needle valve 16 from its seat. Instantly this will allow the air to enter and again fill the radiator. If steam is again turned on there will be an increase of pressure in the radiator and the air which has entered will be forced out again through the stem 2, casing 4 and associated parts.

When the expansion of the expansible member 14 is completed the liquid 35 is not lost because the parts are liquid and air tight. However, when first filling the expansible member 14 the liquid is poured in through the nut 17 and then the threaded end of the needle valve is screwed 100 tightly into place. It is evident that by unscrewing this member the liquid 35 can be removed at any time for repairs or for some other adjustment.

I claim:—

1. An air relief valve of the character described including a hollow cup-shaped base having an inlet opening on one side, an internally threaded flange at the upper part and an integral upstanding guiding pin at the center of the lower part, said pin extending axially of the base, a casing screwed on to said flange, said casing being provided with a threaded upper portion, means presenting a valve seat screwed into said threaded upper portion, an expansible structure 110 formed with a plurality of expansible units arranged in alignment positioned within said casing, a valve member rigidly secured to one of said elements and extending loosely into the means forming said valve seat, a tubular guide 115 permanently secured to the unit opposite the one carrying the valve member, said tubular guide slidingly fitting over said pin so as to prevent swaying movement of the expansible units, a spring resting on the bottom of said base and 120 surrounding said tubular guide, said spring acting to resiliently support the expansible structure.

2. An expansible member having a plurality of expansible units, each unit having concaved top 125 and bottom walls, each wall being flat throughout and having an outwardly pressed annular portion formed with a centrally positioned opening, said outwardly pressed portions being arranged in contact so that the various expansible 130 units will make a series, each unit having annular peripheral walls overlapping and means for connecting said outwardly pressed annular portions together.

GUSTAV RICHARD FICKERT. 145
